UNITED STATES PATENT OFFICE

2,426,850

TRAIN ORDER HOLDING DEVICE

Wiley L. White, Calwa City, Calif.

Application December 8, 1944, Serial No. 567,231

4 Claims. (Cl. 258—23)

1

My present invention, in its broad aspect, has to do with improvements in train order delivery devices. In connection herewith, it is one purpose to provide an improved vertically adjustable post or standard for mounting one or more train order delivery devices and wherein means are provided for automatically positioning the post to present certain faces or sides thereof to the road bed or tracks or directed in line with approaching trains; and to provide means for quickly and accurately adjusting the height of the post or standard, and finally to provide an improved base having means for draining the same or preventing the accumulation of moisture. In connection with the post or standard, other objects and improvements and advantages will be apparent from the detailed description and drawings. Another purpose of my invention is to provide an improved train order delivery device with unique and practical means for detachably mounting one or more of such devices on the post or standard. Each train order delivery device has means for presenting the order or message or the like to a train-man including pivoted, spring controlled arms and supporting or carrying cord for the message or order, or the like. These arms when inactive, are normally maintained in vertical position, and when active, are presented at an angle; the pairs of arms flaring away from each other from the supporting structure to arrange the cord and message therebetween for ready attachment.

In addition to the above, I provide an improved supporting and actuating structure for the arms which is pivotally mounted, but normally maintained in a preferred position, and improved and unique means for actuating the arms. Furthermore, the supporting structure itself is simplified, more practical than has heretofore been suggested, and is designed to reduce the cost of manufacture and maintenance.

Other and equally important objects and advantages may be briefly outlined as follows: (1) I provide means for insuring handy and effective delivery of orders and messages and the like, to trainmen on moving trains without danger of injury or the like; (2) I provide for removal of the devices and supporting posts or standards such as is required by certain statutes and regulations; (3) I provide a device which is easily set up and operated, and (4) I accomplish the above and other ends with a simple, sturdy, practical structure designed to meet the requirements of hard and exacting usage.

While I have described and illustrated a pre-

2

ferred embodiment, it is to be understood that I am not thereby to be considered limited to those specific forms, shapes, sizes, arrangements and construction of parts since minor changes may be resorted to provided they fall within the scope and interpretation of the appended claims.

In the drawings wherein such preferred form is illustrated:

Figure 1 is a vertical elevation of my device, showing the base support in section;

Figure 2 is a vertical section through my delivery device and supporting post;

Figure 3 is a transverse section on the line 3—3 of Figure 2;

Figure 4 is a section on the line 4—4 of Figure 1;

Figure 5 is a section on the line 5—5 of Figure 2;

Figure 6 is a fragmentary side elevation of a part of a supporting post or standard showing the latch to hold the section in adjusted position and mountings for the delivery devices;

Figure 7 is a section on the line 7—7 of Figure 1;

Figure 8 is a transverse section through the post or standard on the line 8—8 of Figure 1;

Figure 9 is a detail of the end of one of the arms showing the cord supporting hook; and

Figure 10 is a section on the line 10—10 of Figure 6.

In the drawings wherein like characters of reference are used to designate like or similar parts throughout the several views:

Numeral 1 designates a suitable concrete or aggregate base block which is designed to be embedded at some suitable point in the road bed 2, or the like, in proximity with the railway tracks to be served by my delivery device. The base block 1 has a triangular, vertically extending opening 3 therein communicating with an enlarged stump or drainage cavity 4. My vertical supporting post or standard 5 is formed with telescoping sections 6 and 7 each of which is triangular in cross-section, and the lower section 6 is seated in opening 3 of the base block which constitutes its socket. An angular foot 8 is attached to the section 6 which facilitates placing the standard in the socket and limits the downward movement of section 6. The triangular formation of the socket 3 and standard or post is to facilitate and automatically present supporting faces of the post or standard to the tracks since my device may have to be set up at night

or when visibility is poor. Suitable grouting or

a rim 9 may be placed about the mouth of opening 3.

My standard or post may be easily adjusted as to height by raising the section 7, and section 6 has a series of vertically aligned openings 10 in one side thereof to receive a latching pin 11 carried by the section 7. The latching pin 11—see Figure 7—is slidably mounted in a keeper 12 having a base 13 provided with a U-shaped handle 14 having a grip portion 15. The pin 11 has a flange 16, and a spring 17 positioned about the pin engages the flange and keeper to normally urge the pin into an opening 10. The keeper and base may be welded or otherwise, attached to section 7 and an operating lever 18 is pivotally mounted on the handle and has a camming arm 19, slotted as at 20 to receive the stud 21 on the lever which functions to withdraw the pin against the tension of the spring 17 to release the sections for adjustment. The pin 11 has a beveled end 22 and each opening 10 is beveled as at 23 to facilitate seating of the pin. The handle 15 also serves to facilitate moving the section 7 with respect to section 6 to make adjustments as to height. Sections 6 and 7 have registering vertical slots 24 and 25 respectively substantially extending from end to end of each of said sections.

My train order or message delivery devices are spaced at intervals on the vertical standard, and there may be one or several of them. If there are several devices, as here described and illustrated, each can carry an order or message, and as a train passes, a message can be removed from one device by the engineer, another by the conductor further along the train and so on. A description of one device will suffice for all, since all devices are identical in construction and operation.

I provide a base plate 26 which is substantially U-shaped, and engages the section 7 on two faces—as shown in Figure 3—and the shorter arm 27 may be braised or soldered to the standard as at 28 or the lower arm 29 may be bolted as at 30—see Figure 10—in the slots 24 and 25. To the bight 31 between the arms 27 and 29 of the base plate is riveted as at 32 a U-shaped spring clip 33 which may be used to carry a flash light, or the like, to illuminate the delivery device at night. The spaced arms of the clip have arcuate portions 34 and flared back ends 35 to permit ready insertion of a flash light (not shown).

Formed in the longer arm 29 either midway the sides or toward one side are in-struck depressions or recesses 36 having an enlarged part 37 and a depending restricted channel 38. There are preferably two slots or depressions vertically aligned, and preferably at the point in the plate where the slots are located, the plate is bent outwardly to form a wide boss or elevated portions 39—see Figure 3. A U-shaped bracket 40 having spaced parallel arms 41 has two studs 42 which are receivable in the depressions or slots 36. The heads 43 of the studs pass through the enlarged parts 37 and then down into the restricted parts 38 to removably retain the bracket on the base. The fingers 36a formed by striking in the depressions bear against the heads 43 of the studs to prevent looseness or accidental displacement. Pivotally mounted by a pin 44 journaled in the arms 41 of the bracket 40 is a U-shaped support 45 the arms of which flare outwardly as at 46 in opposite directions. The bight 47 of the support lies back of the pin 44 which passes through openings in the arms in front of the bight, and

carried by the bracket 40 is a cylindrical housing 48 carrying a spring 49 bearing against the shoulder 50 of a slidable cylindrical foot 51 which engages the bight 47 and has a shank 52 extending into the spring—see Figure 2. The foot normally holds the support in the position shown in Figures 1 and 2, but when pressure is applied to the support sufficient to overcome the tension of the spring 49 the support will pivot in either direction laterally of the bracket as shown by the direction arrows and dotted line position in Figure 3. Suitably secured between the flared portions 46 of the support is a substantially triangular housing 53 having side plates 54 and a front wall 55 but no top and bottom walls, and the front wall 55 terminates short of the forward corners of the housing. A bolt 56 extends between the side plates and mounts a leaf spring 57, the purpose of which will hereinafter appear.

10 Pivots mounted between the side plates 54 on studs 58 are elongated tubular socket members 59 which extend from a point adjacent the pin 44 to a point well forward of the front wall 55, as shown in Figures 1 and 2. In their active positions, as shown in Figures 1 and 2, these socket members 59 diverge outwardly at an angle to each other and lie along the edges of plates 54; they are, however, normally positioned in an inactive position—shown in dotted lines in Figure 2—which is parallel with the standard 5. The sockets are normally held in an inactive position parallel with standard 5 by springs 60 which have eyes 61 at their ends, one end of each spring being secured by a bent wire anchor 62 to the inner end of a socket member, and the other ends of the springs being secured by a wire anchor 63 to the front wall 55 of the housing. Stop pins 64 between the sockets and attached to the plates 54 prevent further movement of the sockets when they reach the inactive positions parallel with the standard.

40 Mounted in the sockets are arms 65 which may be formed of wood, rubber, plastic or the like—see Figure 9—and each arm has an end cap 66 carrying an outwardly sloping hook-like member 67. A cord 68 is caught under the leaf spring 57 and about the hook-like members 67 when the arms and sockets are in the active full line positions of Figures 1 and 2—that is, extending forwardly in diverging relationship, and the ends of this cord are tied to the order or message 69—as shown in Figure 1—so that the socket and arms are held in active position against the tension of springs 60. When the message or order 69 is 45 grasped, the cord 68 is pulled from the leaf spring 57 and from the hook-like members 67 so that the sockets and arms 65 are released and returned by springs 60 to their inactive position parallel to the standard 5. Since the train may be running at high speed, a further safeguard against possible injury is the pivoting movement, or “give,” provided by pin 44—as shown in Figure 3. Further movement of the sockets 59 and arms toward each other under the tension of the cord 68 is prevented by engagement of the sockets with the ends of the front wall as shown in Figure 2.

60 From the foregoing, it is believed that the operation and advantages of my invention will be apparent.

65 I claim:

1. A train order delivery device, comprising a vertically adjustable standard, a removably mounted base plate on the standard having in-70 struck portions, a U-shaped bracket having studs

removably engaged in the openings of the instruck portions, said bracket carrying a spring pressed foot, a support pivotally mounted in the bracket and engaged by the foot, a hollow substantially triangular housing on said support, tubular socket members pivotally attached at their ends within the housing and extending outwardly therefrom and movable from positions normally parallel with the standard to positions extending outwardly at angles to each other, a spring engaging each socket to urge the same to a position parallel with the standard, stop means to limit the movement of the sockets, arms removably received in the sockets, hooks on the free ends of the arms, a spring clip on the housing, and an order carrying cord engageable with the spring clip and with the hooks to hold the sockets and arms in outwardly extended relatively angular position.

2. The invention as described in claim 1, 20 wherein the housing has side plates and an end and is open at the top and bottom, said tubular sockets being pivoted between the side plates and movable through the open top and bottom, and the springs are connected with said end and with 25 the ends of the sockets, and the stop pins are connected with the side plates to limit the movement of the sockets.

3. The invention as described in claim 1, wherein the base plate has instruck fingers providing openings, and the U-shaped bracket has beaded studs removably received in the openings 5 and restrained from removal by the fingers, and the pivoted support is U-shaped with oppositely flared ends and has a bight portion back of the pivot of the support and is engaged by the spring pressed foot carried by the bracket.
4. The invention as described in claim 1 wherein the base plate has a spring clip attached thereto having opposed curved portions and opposed outwardly flared ends.
